[57] **CLAIM**

The ornamental design for a galley hand pump, substantially as shown and described.

DESCRIPTION

FIG. 1 is a perspective view taken from the top, rear and right side of a galley hand pump showing my new design;

FIG. 2 is a front elevational view thereof;

FIG. 3 is a right side elevational view thereof, the left side being a mirror image of the right side shown.

FIG. 4 is a top plan view thereof;

FIG. 5 is a bottom plan view thereof;

FIG. 6 is a rear elevational view thereof.

Fig. 4.
